FIG. 5. Inventor

By *A. Brand*
Geo. F. Snyder Attorney

UNITED STATES PATENT OFFICE.

ADOLPH BRAND, OF WASHINGTON, DISTRICT OF COLUMBIA.

MATCH-BOX HOLDER.

1,048,285.

Specification of Letters Patent. Patented Dec. 24, 1912.

Application filed April 22, 1912. Serial No. 692,410.

To all whom it may concern:

Be it known that I, ADOLPH BRAND, a citizen of the United States, residing at Washington, in the District of Columbia, have invented certain new and useful Improvements in Match-Box Holders, of which the following is a specification.

This invention relates to certain new and useful improvements in matchbox holders of that class in which is provided a holder for inclosing the matchbox and having provision for sliding movement of the box for access to the matches.

The present invention has for its objects among others to provide a simple and improved device of this character having means for preventing accidental displacement of the matchbox, and to provide a cover or closure so constructed and arranged as to push out the match-containing portion by the act of opening the cover.

I aim further at improvements in the details of construction whereby the inclosing portion and cover are strengthened or reinforced and adapted to better serve the purpose for which they are designed.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification and in which—

Figure 1 is a substantially central longitudinal section through a holder embodying my invention, with the matchbox therein. Fig. 2 is an end elevation with a portion broken away and part in section. Fig. 3 is a longitudinal section taken as on the line 3—3 of Fig. 2. Fig. 4 is a view of the blank from which the top is formed. Fig. 5 is a view of the blank from which the holder proper is constructed.

Like numerals of reference indicate like parts throughout the different views.

Referring to the drawings, 1 designates the blank from which the holder proper is constructed. It has a substantially central longitudinal opening 2, a tongue or tab 3 centrally disposed and the bendable lugs 4 upon opposite sides adjacent the edges. Along or at one side upon opposite sides of the central portion there are stamped out the tongues 5 for a purpose which will soon

be made apparent. This blank is bent along the dotted lines 6—6 to construct an oblong holder of which the central portion 7 of the blank forms one side or rather a bottom and the two portions 8 and 9 of the blank form the opposite sides. When thus formed, the lugs 4, 4 are bent over, as seen in Figs. 1 and 3, to engage the adjacent side 10 of the inclosing portion of the matchbox so as to prevent accidental displacement thereof when the sliding portion 11 of said box is moved. The tongue or tab 3 is bent up at right angles to the bottom, as seen in Fig. 2, see also Fig. 1, which forms a stop for the inward movement of the inclosing portion of the matchbox, as seen in Fig. 1, as well as a stop to limit the movement of the pusher-tongue on the cover, as will be soon explained.

12 represents the blank from which the cover portion is formed. It comprises the central portion 13 which forms the top proper and the two side portions 14 which form the inclosing sides of the cover when the blank 13 is bent along the dotted lines 15 seen in Fig. 4. The central portion is provided with a lip 16 at one end which is designed to be bent down along the dotted line 17 to form a depending portion, as seen in Figs. 1 and 2. The members 14 are provided with openings 18, as seen in Fig. 4, through which the tongues 5 are passed and then bent over, as seen in Fig. 2, to form the pivots or fulcrums on which the cover portion is movable. One of the members 14 is provided with an opening 19 designed to constitute a cigar cutter. The central portion of the blank 13 opposite the lip 16 is formed with an extension or lug 20 and upon opposite sides thereof with the tongues 21. The tongue 20 is designed to be bent along the line 22 and the lugs 21 are designed to be bent along the dotted lines 23 seen in Fig. 4. These, when bent along the lines 23, form the depending wings or wind-guard, as seen in Figs. 1 and 2, the tongue 20 being beaded or rolled, as shown at 24, to form a finger hold by which the cover may be easily manipulated.

The blank 13 upon opposite sides of the tongue 16 is formed with the wings 25 which are designed to be bent along the lines 26 shown dotted in Fig. 4 and are, in turn, provided with the extensions 27 designed to be bent angularly along the dotted lines 28 seen in Fig. 4 to form reinforces for the

wings. When the blank 12 is bent up into form, the wings are bent along the lines 29 and seamed or clenched, as seen at 30 in Fig. 3, in any well known way. The free ends 5 of the wings are rolled or turned, as seen at 31 in Figs. 1 and 2, to form a rounded surface for contact with the end 32 of the sliding portion of the matchbox, as seen best in Fig. 1.

10. The parts are shown in operative relation in Fig. 1 wherein it will be seen that the wings 25 are designed as the cover is moved upon its pivots to pass through the opening 33 in that end of the holder above the extension 3, and with its rounded end engaging the end 22 of the movable portion of the matchbox constitutes a pusher by which said sliding portion is moved outward by the movement of the cover portion in the direction of the arrow seen in Fig. 1. When the sliding portion is pushed back, the end 22 engaging the free end of the pusher, serves to restore the cover to its closed position. The opening 2 serves to disclose the match-
25 scratching portion of the matchbox common in such devices. The upturned end portion 3 serves as a stop to limit the movement of the pusher, as will be readily understood upon reference to Fig. 1.
30. Modifications in detail may be resorted to without departing from the spirit of the invention or sacrificing any of its advantages.

What is claimed as new is:—

1. The combination with a match box 35 holder, of a pivoted cover therefor having a pusher tongue adapted to move a portion of the box, said tongue comprising two wings having reinforced opposite side edges, the adjacent edges of the wings being connected 40 to form a central reinforcing seam, the free end of the tongue being rolled to form a box-contacting portion.

2. The combination with a match box 45 holder, of a cover therefor having a pusher tongue movable within the holder to move a portion of the box, said tongue comprising two wings connected at their adjacent edges and terminating in a box contacting end.

3. The combination with a match box 50 holder, of a pivoted cover therefor formed of a blank bent longitudinally to form a top section and side sections, a lip or extension depending from one end of the top section, and wings integral with the side sections, 55 said wings being bent and connected at their adjacent side edges to form a pusher tongue the free end of which is rolled to constitute a box contacting portion.

In testimony whereof I affix my signature 60 in presence of two witnesses.

ADOLPH BRAND.
